Inventor:
James W. Cain,

William L. Symons
Atty.

UNITED STATES PATENT OFFICE.

JAMES W. CAIN, OF DETROIT, MICHIGAN.

MEANS FOR OPERATING STOP LIGHTS.

Application filed October 23, 1922. Serial No. 596,397.

To all whom it may concern:

Be it known that I, JAMES W. CAIN, a citizen of the United States of America, residing at Detroit, in the county of Wayne and State of Michigan, have invented certain new and useful Improvements in Means for Operating Stop Lights, of which the following is a specification.

My invention relates to the construction of stop lights for vehicles and means for operating such lights.

The invention relating to the construction of stop lights is claimed in divisional application No. 706,365 filed April 14, 1924.

Some of the objects of my invention are: to construct a casing for vehicle stop lights in which the lights may be efficiently arranged; which will be easy to manufacture and which is strong and durable; which is efficiently divided into compartments; which has novel light sockets; which has few parts which will not easily become injured; in which the colors of the tail light and signals are distinctive and efficient; and to construct a switch for operating the light which is strong, efficient, and easily operated.

With these and other objects in view, one embodiment of my invention is shown in the accompanying drawings in which:

Figure 1 presents diagrammatically the general arrangement and important parts of my invention;

Figure 2 is a rear end view of the stop light casing;

Figure 3 is a section on the line 3—3 of Figure 4;

Figure 4 is a section on the line 4—4 of Figure 2;

Figure 5 is a side elevation of my improved switch;

Figure 6 is a central longitudinal section of the switch; and

Figure 7 is a section on line 7—7 of Figure 6, with the washer 65 in plan.

The casing 1 of my stop light may be round, as shown, or it may be oval or of any other suitable shape. The casing face 2 is screw-threaded onto the casing and may be secured by any suitable means, such as a screw 3. As shown in Figure 3, my casing is divided into four compartments in a novel manner by dividing walls 4 and 5. The wall 4 consists of a single piece of metal having upturned flanges 6 by means of which it is attached to the casing in any suitable man-

ner, as by screws 7. The dividing wall 5 is attached to the casing in a similar manner. The wall 5 is bent near the center at right angles, separating the upper part of the casing into two parts by means of the upturned part 8. The casing face is cut away at 9 as a stencil, producing the right and left hand pointers, the word "Stop," and an opening for the tail light. Back of the stenciled casing face is a lens 10. The lower part 11 of this lens, covering the opening for the tail light, is colored red. It will be evident that the lens may be of one or two pieces. The casing has sockets 12 stamped out for the insertion of the required number of lamp bulbs. These sockets may have means, such as screws 12^a, to hold the bulbs firmly. There is an opening 13 from the lower compartment. The casing is attached to a bracket 14 in any suitable manner, as by bolts 15. This casing may have a slot 16 in it for the purpose of attaching the license plate. It will be evident that this plate is illuminated by the light from the lower compartment passing through the opening 13. Bolts 17 may be used to attach the bracket to the usual fender 18.

As shown in the drawings, the lower compartment will contain the tail light 19 having suitable wires 20 to connect it with a battery not shown. A stop light 21 is connected to a special form of switch by wires 22. The left-hand indicator is illuminated by a turning light 23 connected to a switch by wires 24. The right-hand light 25 is connected to a switch by wires, not shown, similar to the wires 24.

My improved switch consists of a casing 50 comprising an upper part 51 and a lower part 52. This casing may have suitable insulation 53. Each of the parts of the switch casing has a flange which is joined by screws 54. Within the casing is a pulling rod 55 having an outer insulated part 56. Attached to the upper part of this rod by swaging or by screw threads is a contact washer 57 having the usual return wire 58 connected to it. In the lower part of the switch casing is a spring 59 attached to a half spool 60 by suitable means, such as a pin 61. Placed above the spool is an insulating washer 62 of fibrous material. In the upper part of the switch casing is a spring 63 having a wire connection 64. A C-shaped insulating washer 65 made of fibrous material is placed 110

above the insulating washer 62 and above the lower end of the contact spring 63. A retaining band 66 which is shaped in cross-section to surround the flanges on the parts 5 of the switch casing may be attached at a suitable place by screws 67. The switch is operated by a connection 68 between the rod and a suitable hand or foot lever. It will be apparent that if the rod is pulled down 10 against the pressure of the spring in the lower part of the switch casing, the washer will make contact with the spring in the upper part of the switch casing, causing the "stop" or right or left hand signals to operate depending on which switch rod is pulled.

Having described my invention, what I claim and desire to protect by Letters Patent is:

1. An electric light switch comprising a 20 casing, a rod in said casing having one end thereof extending through said casing, a spring abutting spool attached to said rod and surrounding said rod, a spring surrounding said rod; one end of said spring abutting said spool and the other end of said spring abutting an end of said casing; an insulating wall dividing said casing into upper and lower compartments; a spring in

said upper compartment surrounding said rod; a contact washer attached to the upper 30 end of said rod; an electric wire connection to said upper spring; a return electric wire connection to said washer and means to bring said washer in contact with said spring to operate said switch.

2. An electrical switch comprising a casing, an insulating partition in said casing dividing said casing into two compartments, a draw rod in said casing having one end thereof extending out of said casing, spring 40 abutting means attached to said rod, a spring member surrounding said rod, one end of which abuts said abutting means and the other end of which abuts one end of said casing, whereby the switch is held normally in 45 inoperative position; a contact attached to one end of said rod, said contact having an electrical connection, a spring contact means surrounding said rod, said contact having an electrical connection, one end of said spring 50 contact being held by said insulating partition and means to move said rod to form an electrical circuit.

In testimony whereof I affix my signature.

JAMES W. CAIN.
